UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed July 5, 1923. Serial No. 649,423.

This invention relates to improvements in anti-friction bearings.

One object of the invention is to provide an anti-friction bearing, especially adapted for use as a side bearing on railway cars, wherein the anti-friction element proper is automatically self-centered under the influence of gravity and without the aid of spring or other fragile parts likely to get out of order.

More specifically, an object of the invention is to provide a truck bolster side bearing wherein the anti-friction element is counter-weighted, the counter weights being so associated with the housing or retaining member that the desired relation between the anti-friction element and the housing is retained at all times and in all positions of the anti-friction element.

In the drawing forming a part of this specification, Figure 1 is a vertical sectional view taken through the ends of the body and truck bolsters of a railway car showing my improvements in connection therewith. Figure 2 is a top plan view of the side bearing proper shown in Figure 1. And Figure 3 is a vertical, sectional view corresponding substantially to the line 3—3 of Figure 1.

In said drawing, 10 denotes the upper portion of a truck bolster and 11 the underside of an opposed body bolster of a railway car, the improved bearing being shown attached to the truck bolster and comprises, broadly, a retaining member, housing or base casting A; an anti-friction element proper B; and a pair of counter-weight discs C—C.

The housing A is preferably in the form of a malleable casting having a bottom wall 12, vertical side walls 13—13, and curved end walls 14—14, the latter conforming to the contour of the anti-friction element when the latter is in either of its extreme end positions. The housing is provided with suitable end lugs 15 by which it is adapted to be riveted or otherwise rigidly secured to the bolster. Preferably, also, a loosely inserted hardened wear plate 16 is employed in the bottom of the housing and upon which

the element B is adapted to roll back and forth.

The anti-friction element proper B is shown in the form of a true cylindrical roller although the form may assume other shapes, as will be apparent to those skilled in the art. Said element B is provided at a point below the center thereof when it is in central position with a transversely extending opening 17 within which is received a pin 18 having its ends extended beyond the ends of the element B. Loosely rotatably mounted on said ends of the pins 18 are the two counter-weight discs C whereby said discs are adapted to rotate with respect to said pin 18 during the actuation of the bearing.

Each of said counter-weight discs C is received within a specially formed guide recess 19 formed on the inner face of the corresponding side wall of the housing. Each of said recesses 19 has a curved bottom edge 20, rounded end edges 21, the latter being so extended and merged as to provide a downwardly extending rounded projection 22 at the center and top of the recess, as clearly indicated in Figure 1. The contours of said recesses 19 are so formed as to correspond with the lines generated by the upper and lower points of the discs C when the latter are moved by the element B to either side of central position so that said discs C will be prevented from having any appreciable amount of play within said recesses 19, regardless of the position of the anti-friction element B. The pin 18 is preferably inserted through suitable openings 23 formed in the side walls of the housing A, said pin being retained in proper position by plugs 24—24 in said openings 23, the plugs being held by cotters 25—25.

The anti-friction element B may also be provided with another transversely extending aperture 26 at a point above its center when in central position and within which is received a retaining pin 27, laterally extended ends of the latter working within slightly curved recesses 28 formed in the side walls of the housing A. Said pin 27 is en-

tered through suitable openings 29 in the side walls of the housing and retained in position by plugs 30, the latter being held by cotters 31. To reduce the weight of the 5 housing A, the side walls thereof may be cored as indicated at 32-32, the openings thus formed also acting as vents to permit foreign matter to be washed or blown out.

It is believed the operation of the device 10 will be understood from the preceding description, it being evident that the counterweights C will be elevated as the element B is moved to either side of central position and hence said counter-weights will be in 15 a position to effect automatic return of the element B. By loosely rotatably mounting the discs C on the pin 18, possibility of binding is reduced to a minimum while at the same time, the relative positions of the element 20 B and housing A are always maintained, that is, opportunity for the element B to shift bodily with respect to the housing A without a rolling action is prevented.

I have herein shown and described what 25 I now consider the preferred manner of carrying out my invention, but the same is merely illustrative and I contemplate all changes and modifications that come within the scope of the claims appended hereto.

30 I claim:

1. In a side bearing for railway cars, the combination with a housing adapted to be secured to a truck bolster and provided with a bottom bearing surface; of an anti-friction roller disposed within said housing and adapted for rolling movement to either side of central position therein; a pin extending through said roller and located at a point below the center of said roller when the latter is in central position; circular counterweight discs rotatably mounted on the ends of said pin, said discs being received in guide recesses formed on the inner opposed faces of the housing, the contours of said recesses 35 conforming to the lines generated by said discs as the latter are moved by the roller to either side of central position; and a second pin extending through said roller at a point above its center when in central position, the ends of said pin working within 40 recesses provided on the opposed inner faces of the side walls of the housing.

2. In an anti-friction bearing adapted for attachment to a bolster or the like, the combination with a housing; of an anti-friction element disposed within said housing and adapted for rolling movement to either side of central position therein; a pair of pins projecting through both ends of said element, said pins being in vertical alinement when the element is in its central position; and counterweights carried on both the projecting ends of the lower of said pins, the walls of said housing opposite the upper of 45 said pins and opposite said counterweights

having guide recesses closely conforming to the lines generated by said counterweights and said upper pins as they are moved by the roller to either side of central position.

3. In an anti-friction bearing, the combination with a mounting; of an anti-friction element co-operating with said mounting and adapted to move to either side of central position thereof, said element being provided with eccentric, spaced projections 70 on its ends, the lowermost of said projections being provided with circular members rotatably mounted thereon and providing counter-weights; and means associated with said mounting and providing spaced guides for the snug movable reception of said projections and said counter-weights, said guides being curved to conform to the paths of movement of said projections and said counter-weights. 75

4. In an anti-friction bearing, the combination with a retainer; of an anti-friction element disposed in said retainer and adapted to be moved to either side of central position, said element being provided with eccentric projections; and circular members rotatably mounted on said projections and providing counter-weights for retaining said element in central position, said retainer being provided with guides having their guiding walls spaced apart to afford minimum clearance to permit rotation of said circular members, said guides being curved to conform closely to the paths of movement of said counter-weight members. 80

5. In an anti-friction bearing, the combination with a retainer, of an anti-friction element disposed in said retainer and adapted to move to either side of central position, said element being provided with spaced eccentric projections, one of which is in a lowermost position when said element is in its central position, and the other of which is in an uppermost position, said lowermost projection being weighted, the walls of said 90 retainer being provided with a separate independent guide slot for each of said projections, the walls of each of said guide slots being spaced apart to provide a snug sliding fit with each of said projections, said 95 walls being curved to conform to the paths of movement of said projections, and the walls of each guide slot terminating in spaced relation with reference to the walls of the other guide slots. 100

6. In an anti-friction bearing, the combination with a retainer; of an anti-friction element disposed in said retainer, said element having fixed spaced diametrically disposed eccentric projections at its end, said 110 retainer being provided with a separate and independent guide slot for each of said projections, whereby one of said projections is prevented from entering the guide slot of the other, the opposite walls of each of said 115 120 125 130

guide slots being spaced apart to permit a minimum of operative clearance for said projections, and said guide slots being curved in a path common with the path of movement of said projections during the movement of said anti-friction element to either side of central position, whereby said element is prevented from bodily shifting with refer-

ence to said retainer during rotation of said element, and maintained in assembled relation with said retainer. ¹⁰

In witness that I claim the foregoing I have hereunto subscribed my name this 30th day of June 1923.

JOHN F. O'CONNOR.
